UNITED STATES PATENT OFFICE

2,370,036

AERIAL WEAPON

Albert S. Howell, Culver, Ind., assignor to The
Bell & Howell Company, Chicago, Ill., a corpo-
ration of Illinois

Application July 5, 1941, Serial No. 401,130

6 Claims. (Cl. 89—36)

My invention relates to an aerial weapon to be used by and against aerial vehicles such as aeroplanes, and has for objects the provision of an effective weapon which is fluid, particularly air, suspended to await engagement by a fluid supported vehicle such as an aeroplane with a view toward the destruction or at least disablement thereof, which is comparatively inexpensive in its manufacture, which is convenient in the handling thereof prior to and in the placing thereof in use, and which preferably involves a plurality of weapon units desirably related for the convenient handling and launching thereof in multiple and the placement thereof into use in desired space relation.

The invention will be better understood by reference to the accompanying drawings, in which

Figure 1 is a partial side elevational view of cutting device for cutting one embodiment of the weapon or cutting element of the weapon of my invention;

Figure 2 is a partial end elevational view of the same;

Figures 3, 4 and 5 are partial face views of variations of the cutting elements of the weapon of my invention as cut by the device of Figures 1 and 2;

Figure 6 is a diagrammatic view of an apparatus for carrying out the method of making and preparing one form of the cutting elements of the weapon of my invention;

Figure 7 is a partial view of a finished cutting element of the weapon of my invention.

Figure 8 is a face view of a weapon of my invention, showing it in its compact unit form, with parts broken away;

Figure 9 is an opposite face view of the same with parts broken away;

Figure 10 is an edge view of the same with parts broken away and shown in section;

Figures 11 and 12 are edge views of the same at different stages of the release of the weapon from its compact unit form, with parts broken away;

Figure 13 is a side elevation of the multiple unit weapon of my invention showing it in process of launching;

Figures 14 and 15 are respectively a transverse section and a partial side elevational view of another form of the weapon or cutting element of the weapon of my invention;

Figures 16, 17, 18, 19 and 20 are views of an aeroplane in flight in different stages of launch-

ing multiple unit weapons of my invention by the method of my invention; and

Figure 21 is a view showing the weapons of my invention placed in barrage form and showing aeroplane casualties in different stages as effected by my weapons.

Referring to Figure 7, 1 designates one form of the weapon element of the weapon of my invention which consists of a flexible permanently longitudinally twisted ribbon element, preferably of steel, having a longitudinal edge thereof provided with cutting teeth 2, it being observed that the longitudinal twist of the ribbon element presents cutting teeth around an axis longitudinal of the ribbon element.

This cutting element is preferably made and formed in the following manner. See Figures 1, 2, 3 and 6. A linear piece of flat stock 3 is progressively facewise longitudinally cut in toothed form midway of its width to form two untwisted flexible ribbon elements 4, a longitudinal edge of each of which is provided with the cutting teeth 2 as shown in Figure 3. Figures 4 and 5 show respectively ribbon elements 5 and 6 similar to the ribbon elements 4, but having teeth of different form respectively indicated at 7 and 8.

This cutting operation is preferably accomplished, see Figures 1, 2 and 6, by means of a pair of oppositely driven revoluble cutting members 9 and 11 disposed on parallel axes and provided with oppositely disposed circumferential toothed cutting formations 12 disposed in meshing shearing relation and operative to toothedly cut the flat stock 3 into the ribbon elements 4 as the stock is fed linearly therebetween, oppositely facing guides 13 being associated with the cutting members at the cutting station thereof as shown in Figures 1 and 2.

Referring to Figure 6, simultaneously with the cutting operation to produce the toothed ribbon elements 4, the ribbon elements are longitudinally twisted progressively therealong between spaced pairs of revoluble pressure rollers 14 and 15 as indicated at 16, and simultaneously with said cutting and twisting operations the ribbon elements 4 are subjected to a heat treating operation progressively therealong while maintained in their twisted condition by passing the same through a heat treating apparatus generally designated at 17, for permanently setting the ribbon elements in their previously longitudinally twisted condition barring previous permanent setting of the ribbon elements in such condition, or for hardening the ribbon elements in such

twisted condition, assuming them to have been previously permanently set in such condition, or for both permanently setting and hardening the ribbon elements in longitudinally twisted condition as may be instantly expedient. As a result of this procedure, each ribbon element is permanently set in longitudinally twisted form, designated at 18 in Figure 6, and is provided with cutting teeth along one longitudinal edge thereof, as illustrated in Figure 7.

Preferably, simultaneously with one or more of the processes to which the ribbon elements are subjected as hereinbefore described, the ribbon elements are wound in flat spiral coils for compacting the same, and particularly with reference to forming the compacted weapon element of my weapon, as will now be described.

Referring to Figure 6, a carrier member 19 is intermediately rotatably mounted on a stationary shaft 21, and a pair of reeling members 22 are rotatably mounted on the carrier member on parallel axes disposed in diametrically opposite relation with and normal to an axial plane of the rotational axis of the carrier member.

The finished portions 18 of the ribbon elements are attached respectively to the reeling members 22 for the winding of annular flat spiral coils 23 of the ribbon elements thereon simultaneously with the cutting, twisting and heat-treating operations thereon heretofore described, these simultaneous operations facilitating making and packing of the ribbon elements.

In the winding of the finished portions of the ribbon elements on the reeling members 22, the reeling members are oppositely axially rotated by suitable means not shown in the direction of the arrows in Figure 6, and simultaneously with the axial rotation of the reeling members the carrier member 19 is rotated on its rotational axis by suitable means not shown to rotate the reeling members and the coils thereon on an axis extending longitudinally of the portions of the ribbon elements tangential to the coils and in the direction corresponding with the twist of the ribbon elements so that the twist of the ribbon elements does not interfere with the winding thereof into flat spiral coils. The reeling members and the coils thereon are axially offset in correspondence with the lateral displacement of the ribbons so that the coils on the reeling members do not interfere with each other.

My weapon unit is illustrated in Figures 8, 9 and 10, and comprises as follows. The weapon element of this unit as shown consists of a compacted flexible linear cutting element, preferably toothed, which is exemplified in these figures by an annular flat spiral coil 24 of the ribbon cutting element 1 illustrated in Figure 7, and whose manufacture and coiling has previously been described, and the coil 24 is preferably provided with frangible retaining loop elements 25 sequentially binding different sections of the coil to initially retain the same in coil form, these retaining loop elements being applied to the coil as it is wound.

The coil 24 is arranged in a case 26 of flat circular form in corresponding disposition therewith, and the case, or at least one flat face 27 thereof, is of rupturable material such as heavy paper. A compactable parachute 28 of usual construction is arranged in compacted condition in the case and is preferably arranged within the opening of the coil, and is attached to the inner end of the coiled ribbon cutting element 1 for suspension of the cutting element therefrom. In

addition, a compactable parachute-like element 29 of usual construction is arranged in compacted condition in the case, preferably at the side of one face of the coil 24, and is attached to the outer end of the coil 24 in inverted relation with the parachute 28 by a cord 30. Partitions 31 and 32, preferably of rupturable material such as heavy paper, are disposed within the case 26 and on opposite faces of the coil 24, the toothed face 10 of the coil 24 facing the partition 31 and the rupturable face 27 of the case.

A rip cord 33 is attached to the parachute 28, as designated at 34, and extends therefrom in flat spiral form on the inner face of the partition 31, as designated at 35, and then extends outwardly from the case through openings 36 and 37 respectively of the partition 31 and casing face 27, the spiral form 35 of the rip cord being maintained by clips 38 on the inner face of the partition 31.

The weapon may be launched by releasing the case and its contents intact, say from an aeroplane in flight, while retaining the extended portion of the rip cord 33. When the rip cord 20 tensions the central portions of the partition 31 and face 27 of the case are ruptured in circular form by reason of the spiral form 35 of the rip cord, and by reason of the parachute 28 being attached to the rip cord, it is extended or pulled from the case. Upon being freed from the case, the parachute opens, and being attached to the inner end of the cutting element 1, it progressively pulls the cutting element out of the case, as shown in Figure 11, the cutting 25 element progressively rupturing the partition 31 and casing face 27 as it is uncoiled from the inner end thereof and the retaining loop elements 25 being progressively broken as the cutting element is uncoiled, thus effecting a progressive extending action of the cutting element. Finally, the parachute-like element 29 is released from the case as indicated in Figure 12.

Thus the rip cord is operative to facilitate extension of the weapon as an incident of releasing 45 the same so that uniformity in launching is effected, the rip cord either being released from the aeroplane or broken by the tension exerted thereon after it has functioned in the launching.

When the weapon is released and fully extended, it appears as shown in Figure 21, the parachute 28 supporting the same in the air with the cutting element 1 depending linearly therefrom and with the parachute-like element 29 depending 55 from the lower end of the cutting element in inverted relation with the parachute 28.

The weapon in extended or effective condition, as illustrated in Figure 21, remains suspended for a period of time, and assuming an aeroplane 39 60 in flight engages the cutting or weapon element 1 thereof, the weapon element is obviously effective to cause damage thereto.

Assuming the aeroplane 39 to engage the weapon element 1, the parachute 28 and the 65 parachute-like element 29, the latter being attached to the weapon element in spaced inverted relation with the parachute 28, opposingly cooperate in resisting movement of the engaged weapon element 1 extending therebetween with resulting relatively great pressure between the aeroplane and the weapon element and correspondingly great damage to the aeroplane. The parachute 28 and the parachute-like element 29 70 also cooperate in causing the weapon to cling to 75 the engaged aeroplane and hamper its flight, as

illustrated by the aeroplane 41 in Figure 21, which is engaged with a weapon element.

The permanently set longitudinal twist of the toothed ribbon weapon or cutting element 1 by presenting teeth around an axis longitudinal of the ribbon element renders the ribbon element more effective. Another desirable form of an effective cutting or weapon element of the weapon of my invention is illustrated at 42 in Figures 14 and 15. This latter cutting or weapon element as shown comprises a copper-clad steel wire, of which the main or inner portion 43 consists of steel of high tensile strength and the surface coating or sheath 44 consists of relatively soft ductile copper, and cutting teeth forming particles 45 of abrasive material, such as carbide, partially embedded, as by pressure, in the sheath to fix the same therein.

A plurality of my weapons may be placed at spaced intervals to form a barrage as illustrated in Figure 21. In order to facilitate the spaced placement, particularly controlled spaced placement, of a plurality of my weapons, I provide a weapon comprising a plurality of weapon units 46, see Figures 13 and 16 to 20, each weapon unit comprising as heretofore described in detail. The pull or rip cords 33 of all of these units, except an end unit, are spacedly attached to and connect the units in series while the pull or rip cord of said end unit extends therefrom as heretofore described, each rip cord being also as heretofore described tensionally operative on its weapon unit to release the weapon thereof and additionally operative to facilitate extension of its weapon as an incident of said release.

A method of launching my plural unit weapon consists, as illustrated in Figures 16 to 20, in simultaneously releasing all of the weapon units thereof from an aeroplane 47 while in flight and while retaining the extended portion of the rip cord extending from the aforesaid end unit, see Figure 16. Tensioning of this rip cord results in release and extension of the weapon of the first unit, designated at 48, see Figure 17, and breaks this rip cord, then the resistance of the weapon 48 of the first unit separates the first unit from the second unit, then the resulting tensioning of the rip cord of the second unit releases and extends the weapon of the second unit, designated at 49, see Figure 18, and breaks this rip cord, and so on until the weapons of all of the units have been sequentially released and extended, the lengths of the unit connecting rip cords conveniently determining the spacing of the weapons.

A number of aeroplanes may cooperate in launching my plural unit weapons with a view toward quickly developing a comprehensive placement of the weapons. Figure 19 illustrates a second aeroplane 54 launching a plural unit weapon, generally designated at 55, in following relation with the aeroplane 47 of Figure 18.

Figure 20 illustrates weapons placed by the previous plane 47 and designated at 48 to 53 inclusive, and the plural unit weapon 55, which has been released by the following plane 54 subsequent to the release of the first plural unit weapon by the first plane.

The use of my weapon in barrage form is illustrated in Figure 21, in which a lower barrage is shown at 56 and similar upper barrage is partially shown at 57, it being observed that a barrage may be maintained indefinitely by establishing subsequent barrages at the proper altitude as the previous barrage slowly descends.

While I have thus described my invention, I

do not wish to be limited to the precise details described, as changes may be readily made without departing from the spirit of my invention, but having thus described my invention, I claim as new and desire to secure by Letters Patent the following:

1. An aerial weapon comprising a compactable parachute, a flexible linear weapon element attached to and dependable from said parachute, a compactable parachute-like element attached to said weapon element in spaced inverted relation with said parachute, means securing said parachute, said weapon element and said parachute-like element in compacted condition, and a cord extending from said securing means and operative thereon to release said parachute, said weapon element and said parachute-like element.
2. An aerial weapon comprising a compactable 20 parachute, a flexible linear weapon element attached to and dependable from said parachute, a compactable parachute-like element attached to said weapon element in spaced inverted relation with said parachute, means securing said 25 parachute, said weapon element and said parachute-like element in compacted condition, and a cord extending from said securing means and operative thereon to release said parachute, said weapon element and said parachute-like element 30 and attached to said parachute to facilitate extension thereof as an incident of its release.
3. An aerial weapon comprising a rupturable 35 case of flat circular form, a compactable parachute arranged in compacted condition in said case, a flexible linear weapon element compactly arranged in said case in the form of a flat spiral coil disposed correspondingly with the case and having the inner end thereof attached to said parachute for suspension therefrom, and a rip 40 cord extending from said case and rupturably related with a flat face of said case to rupture the same and attached to said parachute for removing said parachute from said case as an incident of rupture of said case.
4. An aerial weapon comprising a rupturable 45 case of flat circular form, a compactable parachute arranged in compacted condition in said case, a flexible linear weapon element compactly arranged in said case in the form of an annular flat spiral coil disposed correspondingly with the case and having the inner end thereof attached to said parachute for suspension therefrom, said parachute being disposed at least partially within the opening of said coil, frangible ties retaining respectively sequential sections of said weapon element in coiled form, and a rip 50 cord extending from said case and rupturably related in spiral form with the central portion of a flat face of said case to rupture said central portion and attached to said parachute for removing said parachute from said case as an incident of rupture of said case.
5. An aerial weapon comprising a case of flat 55 circular form, a compactable parachute arranged in compacted condition in said case, a flexible linear weapon element compactly arranged in said case in the form of a flat spiral coil disposed correspondingly with the case and having the inner end thereof attached to said parachute for suspension therefrom, a compactable parachute-like element also arranged in compacted condition in said case and attached to the outer end of said weapon element in inverted relation with 60 said parachute, and a rip cord extending from 65 said parachute, and a rip cord extending from 70 said weapon element in inverted relation with said parachute, and a rip cord extending from 75 said parachute, and a rip cord extending from

said case and rupturably related with a flat face of said case to rupture the same and attached to said parachute for removing said parachute from said case as an incident of rupture of said case.

6. An aerial weapon comprising a plurality of weapon units, each unit comprising a compactable parachute, a flexible linear weapon element attached to and dependable therefrom, a parachute-like element attached to said weapon element in spaced inverted relation with said parachute, and means securing said parachute, said weapon element and said parachute-like element in compacted condition, pull cords spacedly attached to and connecting said units in series and

tensionally operative on said securing means to release said parachutes, said weapon elements and said parachute-like elements and additionally tensionally connected with said parachutes to facilitate extension thereof as an incident of said release, and an additional pull cord attached to an end unit of the connected series of said units and tensionally operative on the securing means of said end unit to release the parachute, the weapon and the parachute-like element thereof and additionally tensionally connected with the parachute of said end unit to facilitate extension thereof as an incident to its release.

ALBERT S. HOWELL.
